UNITED STATES PATENT OFFICE

135,363

DESIGN FOR A SHRINE

Alfred Ochs, New York, N. Y.

Application February 3, 1943, Serial No. 109,439

Term of patent 14 years

To all whom it may concern:

Be it known that Alfred Ochs, without nationality, residing at 230 Fifth Avenue, New York, in the county of New York and State of New York, has invented a new, original, and ornamental Design for a Shrine, of which the following is a specification, reference being had to the accompanying drawing, forming part thereof.

Fig. 1 is a front elevational view in the closed state;

Fig. 2 is a horizontal sectional view taken on line 2—2 of Fig. 1 and

Fig. 3 is a perspective view in the opened state of the miniature shrine embodying my new design.

I claim:

The ornamental design for a shrine, as shown.

ALFRED OCHS.
